United States Patent Office

Des. 211,295
Patented June 4, 1968

211,295

PENCIL HOLDER

Gerald D. Wolf, P.O. Box 304,
Oak Grove, Mo. 64075

Filed May 1, 1967, Ser. No. 6,891

Term of patent 14 years

(Cl. D74—5)

Fig. 1.

Fig. 2.

Fig. 3.

Fig. 4.

FIG. 1 is a perspective view of a pencil holder showing my new design;

FIG. 2 is a top plan view;

FIG. 3 is a right side elevational view; and

FIG. 4 is a rear view.

A pencil is shown in broken lines in FIGS. 2-4 for illustrative purposes only.

I claim:

The ornamental design for a pencil holder, as shown and described.
